UNITED STATES PATENT OFFICE.

JOHN H. ROBERTS, OF SYRACUSE, NEW YORK, ASSIGNOR OF ONE-HALF TO CHARLES W. SALISBURY, OF CORTLAND, NEW YORK.

COIN-CONTROLLED NEWSPAPER-VENDING MACHINE.

1,314,217.

Specification of Letters Patent. Patented Aug. 26, 1919.

Application filed June 8, 1917. Serial No. 173,541.

To all whom it may concern:

Be it known that I, JOHN H. ROBERTS, a citizen of the United States of America, and resident of Syracuse, in the county of Onondaga, in the State of New York, have invented new and useful Improvements in Coin-Controlled Newspaper-Vending Machines, of which the following, taken in connection with the accompanying drawings, is

10 a full, clear, and exact description.

This invention relates to certain improvements in coin-controlled newspaper vending machines, involving the use of a spring-actuated support upon which the papers are stacked and a manually-operated coin-controlled ejector mechanism for displacing the papers one by one from the stack into a delivery passage in the front of the case from which the operator may withdraw the selected paper at will.

These papers are usually folded along their longitudinal center and afterward along the transverse center so that the folded sheet is approximately one-fourth the area 25 of the full sheet, and is preferably vended in this condition.

One of the objects is to enable the papers to be stacked in this folded condition one upon the other and the uppermost paper 30 ejected into the delivery opening in the case without mutilation or displacement of the remaining papers.

Another object is to provide a simple form of ejector mechanism having relatively 35 movable members adapted to be locked to each other by a coin between them and to connect one of said members with an operating lever whereby both members will be operated to eject the uppermost paper 40 only when locked together by the coin.

A further object is to render the ejecting mechanism dependent upon the introduction of a plurality of, in this instance two, coins in succession and in such manner 45 that the second one only will be effective in establishing a lock between the relatively movable parts of said mechanism.

A still further object is to utilize the coin not only as a locking means between the 50 relatively movable parts, but also the means whereby these parts are released one from the other and the coin automatically released from both parts to drop into a suitable receptacle provided therefor.

55 Other objects and uses relating to specific

features of the apparatus will be brought out in the following description.

In the drawings—

Figure 1 is a perspective view of a coin-controlled newspaper vending machine embodying the features of my invention.

Fig. 2 is an enlarged transverse vertical sectional view of the same device taken on line 2—2, Fig. 1.

Figs. 3 and 4 are horizontal sectional views taken, respectively, in the planes of lines 3—3, and 4—4, Fig. 2.

Fig. 5 is a detail vertical sectional view taken on line 5—5, Fig. 3.

Fig. 6 is a detail sectional view through the coin guide taken in the plane of line 6—6, Fig. 2.

The newspapers to be vended, together with the ejecting mechanism therefor, are housed within a suitable case —1— having 75 a top lid —2— and a front door —3—, both of which are normally locked to protect the interior mechanism and papers, but may be opened at will for inspection and repairs, the function of the front door being more 80 for the purpose of introducing the folded papers in refilling, said case being of just sufficient size to easily receive said papers and permit their free vertical movement in a manner hereinafter described.

The interior of the case is preferably divided near the top by a horizontal partition —4— into lower and upper compartments —5— and —6—, the lower compartment serving to receive a stack of papers, 90 as —a—, together with the support therefor and certain portions of the ejecting mechanism, while the upper chamber serves to receive certain other parts of the ejecting mechanism, including the operating lever. 95

Front and rear pairs of upright guide rods —7— and —8— are supported within the chamber —5— between and by the bottom of the case and partition —4— and constitute guides along and upon which is 100 movable a platform or follower —9— for supporting the stack of papers —a—, the rear pair of rods —7— also serving as limiting stops or abutments for alining the rear edges of the papers vertically, and for this 105 purpose are spaced apart a distance less than the width of the folded papers when resting upon the platform —9—, while the front guide rods —8— are spaced apart a distance greater than the width of the folded 110

papers to allow the latter to be inserted between them upon said platform when the front door —3— is open.

The platform or follower —9— with the 5 stack of papers —a— thereon is spring-pressed upwardly by a coil spring —10— having its lower end resting upon the bottom of the case and its upper end bearing against the under side of the platform —9—, 10 while the uppermost paper engages a limiting stop consisting, in this instance, of an ejector plate —11— which is mounted upon the movable lengthwise or forwardly and rearwardly extending guide rods —12—, as 15 shown more clearly in Figs. 2 and 4.

These guide rods are preferably supported in a slightly inclined plane a relatively short distance below the partition —4— and have their rear ends secured to the rear wall of 20 the case, while their front ends are bent upwardly and fastened to blocks —13— on the front wall of the case.

The ejector plate —11— is disposed in about the same plane as the lower edges of 25 the guide rods —12— and has its opposite edges provided with tubular sleeves —14— slidably mounted on the guide rods —12— to allow said plate to move forwardly and rearwardly in a manner hereinafter described, and at the same time constituting a stop for limiting the upward movement of the papers.

A catch plate —15— is hingedly mounted at —16— in upstanding ears —17— on the 35 rear end of the ejector plate —11— and is provided with a series of pins —18— projecting through suitable apertures in the plate —11— a sufficient distance below the under side thereof to engage the rear folded 40 edge of the uppermost paper only, the lower ends of said pins being preferably hook-shape or slightly bent forwardly and are arranged in a lengthwise row in substantially the same vertical plane as that in 45 which the rear upright guide rods —7— are located when the ejector plate —11— is at the limit of its extreme rear movement or normal position as produced by retracting spring —19—.

50 The catch plate —15— may be rocked about the axis of the pivots —16— by means of an adjusting screw —15'— to vary the degree of projection of the lower ends of the pins —18— below the plate —11— according to the thickness of the papers to be vended.

Suitable means is provided for moving the ejector plate forwardly against the action of the retracting spring —19— to cause 60 the catch pins —18— to force the uppermost paper forwardly into a delivery passage —20— which is provided in the front wall of the case just above the door —3— and in the plane of movement of the ejector 65 plate —11—, and for this purpose the plate

—11— is provided with a pair of upstanding ears —21— to which is secured an arm —22— extending upwardly through a forwardly and rearwardly extending slot —23— in the partition —4— and having its 70 upper end offset laterally at —24— to form a coin abutment, as shown more clearly in Fig. 3.

A horizontally swinging rock arm —25— is pivoted at one end at —26— to the partition —4— and has its opposite end bifurcated to receive the offset —24—, the opposite fingers of the arm —25— being provided with longitudinally elongated coin slots —27— which are normally aligned with the 80 delivery end of a superposed coin chute —28— (see Figs. 2 and 5).

A stationary coin rest —29— lies directly under a portion of the lower coin slot —24— when the arm —25— is in its normal position to temporarily support the coin after the latter is deposited from the chute —28— into the slots —27—.

These coin slots —27— are normally disposed just at the rear edge of the offset 90 —24— which constitutes a coin abutment for coöperation with the coin slots —27— so that when a coin is present in said slots and the inner end of the arm —25— is rocked forwardly, the coin will abut against the 95 rear edge of the offset —24— and thereby move the ejector plate —11— in the same direction to force the uppermost paper into the delivery passage —20— in the front of the case, from which it may be drawn by 100 the operator.

The means for rocking the lever —25— consists of a hand lever —30— having its rear end pivoted at —26— and its forward end extending through a laterally elongated 105 slot —31— in the front of the case just above the partition —4—, said lever being connected by a link —32— to the inner end of the rock arm —25— and is normally retracted by a spring —33—, shown more 110 clearly in Fig. 3, whereby the free end of the lever is normally disposed at the left-hand end of the slot —31—.

Any suitable means may be employed for conducting the necessary coin or coins to the 115 delivery chute —28—, and for this purpose I have provided a coin guide —34— incased within a supplemental housing —35— on the top of the case —1— and having its front end registering with an inlet —36— and 120 its rear end leading to the upper end of the coin chute —28—, as shown more clearly in Fig. 2.

In many instances, the vending price of the paper is two (2¢) cents, requiring the insertion of two coins in succession into the guide —34—, and in order to prevent the operation of the ejector plate —11— upon the insertion of a single coin and to allow its operation upon the insertion of the second 130

coin, I have provided the chute —28— with a branch delivery passage —37— located at one side of the normal position of the bifurcated end of the arm —25— and offset abutment —24—, and have also provided a coin deflector —38— which is preferably pivoted at the junction of the branch passage —37— with the main passage —28— so as to enable its upper end to move to opposite sides of the delivery end of the guide —34—, said deflector being provided with limiting stops —39— for engaging opposite sides of an underlying portion of the chute —28— to limit the movement of the deflector in one extreme position or the other.

These stops —39— alternately project into the passages —28— and —37—, respectively, as the deflector —38— is moved to opposite sides of the delivery end of the coin guide —34— so that a coin emerging from the guide into the chute —28— will be deflected by the member —38— on to the stop which projects across its passage, the weight of the coin being sufficient to depress said stop and rock the member —38— to the opposite side of the delivery guide so that another coin deposited in the chute will be deflected on to the opposite side, thereby restoring the deflector member to its supporting position.

For example, assuming that the deflector —38— is in its normal position, as shown in Fig. 2, and that a patron is desirous of obtaining a two-cent paper, he then places the first coin in the guide —34— which falls upon the right-hand stop —39—, thereby rocking the deflector to the right of the delivery end of the guide and allowing the coin to pass to drop downwardly at one side of the abutment —24— into a suitable receptacle —40— underlying the branch passage —37—.

The patron then inserts another coin into the guide —34— which is delivered on to the left-hand stop —39— and thence into the slots —27— just at the rear edge of the abutment —24— where it is supported temporarily upon the rest —29—.

The patron then rocks the hand lever —30— to the right against the action of the retracting spring —33—, thereby rocking the member —25— with the coin therein forwardly against the abutment —24— which forces the ejector plate —11— forwardly to eject the first underlying paper —a— into the delivery passage —29— from which it may be withdrawn by the patron.

It will be noted that the abutment —24— and ejector plate actuated thereby move in a straight line forwardly and rearwardly, while the free end of the arm —25— with the coin therein moves in an arc about the axis of the pivot —26—, thus causing the coin to slide along the rear edge of the abutment —24— during the operation of ejecting one of the papers, said abutment being of

such length as to cause the desired forward movement of the ejector plate before the coin disengages therefrom, at which time the coin slot will be directly over the receptacle —40—, the disengagement of the coin from the abutment —24— allowing the spring —19— to return the ejector plate —11— and abutment —24— to its normal starting position, and as soon as the patron releases the lever —30— after ejecting one of the papers, said lever and rock arm —25— will also be returned to their normal positions by the lever —33—, ready for a repetition of the operation previously described.

It will be noted from the foregoing description that the ejector plate returns to its normal position in advance and independently of the operating lever —30—, and at the end of its return movement, it serves to operate an alarm in the form of a bell —41— through the medium of an operating member —42— which is secured to the arm —22— on the ejector plate carrying the abutment —24—.

Suitable means is provided for retaining the remaining papers —a— in their stacked position upon the platform or follower —9—, while the uppermost paper is being removed, said means consisting, in this instance, of a pair of toothed jaws —43— pivotally mounted upon the inner faces of opposite sides of the case —1—, in such manner that the rear toothed edges may engage the adjacent edges of the paper next adjacent to the uppermost paper, said jaws being spring-pressed toward the papers by springs —44—, Fig. 2, but the inward movement thereof is limited by stops —45—, Fig. 4.

The operation of my invention will now be readily understood upon reference to the foregoing description and accompanying drawings, but it is evident that certain changes may be made in some of the details without departing from the spirit of this invention.

What I claim is:

1. In a coin controlled vending machine, the combination of the case having a delivery passage, means spring pressed upwardly for supporting a stack of articles to be vended so that the upper one will register with the delivery passage, a stop plate for engaging the uppermost article and slidably back and forth in its own plane, yielding means for holding the plate in a normal position, means on the under side of the plate for engaging one edge of the uppermost article and displacing the same from a stack as said plate is moved from its normal position; a coin receiver movable in the direction of the movement of the plate, a coin chute for delivering a coin into the receiver, means for operating said receiver, an abutment on said plate projecting into the path of the movement of the coin in the receiver

110

105

110

115

120

125

130

for operating said plate to displace the uppermost article from the stack, said receiver and abutment being movable in diverging paths from their normal position to cause the coin to disengage from the abutment when the parts are moved to a certain position.

2. In a coin controlled vending machine the combination with an ejector plate and means for feeding the articles to be vended, one by one, against the underside of said plate to be ejected thereby, of a coin-chute, a horizontally swinging arm having means for receiving a coin from said chute when in one position and for releasing said coin when in another position, an abutment on the ejector plate in the path of movement of the coin in the receiver and means for rocking said arm to cause the coin to engage said abutment and thereby operate the ejector plate to eject the article engaged therewith.

3. In a coin controlled vending machine, the combination of a horizontally swinging arm having a coin receiver, an operating lever therefor movable about an axis parallel with that of said arm, a slidable ejector for the articles to be vended having an abutment in the path of movement of a coin in

said receiver whereby the ejector is operated to eject one of said articles as the receiver is moved from its normal position, said coin receiver and abutment being movable in diverging paths from their normal position to cause disengagement of the coin from said abutment when moved to a certain position.

4. In a coin controlled vending machine the combination of a slidable ejector plate having adjustable means for engaging one edge of an article to be vended for expelling said article when the plate is moved in one direction from its normal position, a horizontally movable rock arm above the ejector plate and provided with a slot to receive a coin, a coin chute for conducting a coin into said slot, an abutment on the ejector plate projecting into the path of movement of the coin in the slot whereby the movement of the rock arm from its normal position will operate the ejector plate, and a horizontally movable hand lever also above the plate and connected to said arm for rocking the same.

In witness whereof I have hereunto set my hand this 31st day of May, 1917.

JOHN H. ROBERTS.
